DETONATING FUSE

Raymond L. Graumann, Alexandria, Va.

Application May 4, 1938, Serial No. 206,041

9 Claims. (Cl. 102—79)

(Granted under the act of March 3, 1883, as
amended April 30, 1928; 370 O. G. 757)

1

This invention relates to a fuse for detonating the bursting charge of a projector and has among its several objects:

To provide a fuse that will cause the burst of a projectile with high order detonation after a delay that permits penetration of an armor plate;

To provide means to maintain the fuse in unarmed condition until after firing;

To provide centrifugally operated means for conditioning the fuse for detonation;

To provide a fuse with the parts so arranged that while in the unarmed condition the detonator of the fuse may be exploded without affecting the booster charge carried by the fuse or the bursting charge of the projectile in which the fuse is assembled;

To provide novel means for locking the movable parts of the fuse in firing position.

In the drawings:

Fig. 1 is a longitudinal section of my novel fuse in the unarmed condition;

Fig. 2 is a detailed sectional view, substantially at right angles to the plane of Fig. 1, of a portion of the fuse illustrating the relation of the parts in the firing position;

Fig. 3 is a fragmentary view on a larger scale disclosing the novel means for locking the parts in the firing position;

Fig. 4 is an enlarged detailed view, in section, of the delay element;

Fig. 5 is a fragmentary sectional view disclosing the relation of certain parts of the fuse in the unarmed position;

Fig. 6 is a transverse section taken on the line 6—6, Fig. 1, showing the guide and anti-friction means for the auxiliary plunger.

The fuse constituting the subject of the present invention is intended for use in the base of a projectile, and in common with other fuses of this general type the body 7 is provided with screw threads 8 for engaging threads in the fuse opening in the projectile. If desired, tracer charge 9 may be inserted or the space designed to receive the tracer may be closed by a plug if the tracer is not used.

The movable parts of the fuse comprise an auxiliary plunger 10 provided with longitudinal grooves 11 wherein are mounted ball bearings 12 to guide the auxiliary plunger in the body 7 and permit free movement thereof by momentum upon impact of the projectile, the balls being held in position by a ball retainer 13.

Immediately ahead of the auxiliary plunger and in contact therewith is the plunger 14 that

2

carries the delay element. Plunger 14 is formed with a circumferential flange 15 that is engaged by spring detents 16 that hold the plunger in the unarmed position, as shown in Fig. 1. The rotation of the projectile after firing sets up centrifugal forces that move the detents 16 outwardly and permit the plunger 15 to move forwardly upon impact of the projectile, but such forward movement before impact is prevented by anti-creep spring 17 that tends to hold the plunger 15 in the unarmed position. Other detents 18 are provided in the fuse cap 19 between the firing pin 20 and the forward end of the delay element, thus providing an additional safety factor until after the projectile is fired.

The delay element 50, shown in detail in Fig. 4, is mounted in the plunger 15 where it is retained by engagement of screw threads 21 with coacting threads in the plunger 15. At the forward end 20 of the delay element is a sensitive primer 22 seated on primer retaining cup 51 in primer container 52 and disposed to be struck by firing pin 20 when the parts are moved into firing position, as seen in Fig. 2, upon impact of the projectile. 25 The expansion of the products resulting from the explosion of primer 22 effects two results:

First, the firing pin 23 that is normally held inoperative by a shear pin 24 is driven to explode the primer 25 which has an anvil 26 to cooperate with the firing pin;

Second, the cup 27 of deformable metal, for example copper, is expanded into recesses 28 in the cap 19 and thereby locks the parts of the fuse in the firing position with all the elements correctly aligned to transmit the explosion as desired, the gases passing through openings 33 to act upon cup 27. The deformation of the cup 27 into the recess 28 is shown on an enlarged scale in Fig. 3.

40 The flames and hot gases resulting from the explosion of primer 25 are caused to pass through a baffle 29 having a chamber 30 communicating with primer 25 by passages 31 in anvil 26 and thence by radial openings 32 to longitudinal grooves 33 and thence to the delay pellet 34.

45 The passage of the hot gases into the forward part of the fuse body is prevented by an obturating ring 35 of lead or other suitably plastic metal that is squeezed out into tight contact with the plunger 15 by placing the pellet container 54 in position in the plunger, placing the obturating ring 35 thereon, seating the baffle 29 against the obturating ring 35 and applying pressure to the baffle to deform the obturating ring against the plunger 15.

Mounted in the plunger 15 adjacent delay pellet 34 and in communication therewith through opening 36 is the detonator charge 37 with detonator lead-outs 38 to propagate the ignition to booster charges 39 that are retained in position by a cup 40 surrounding fuse body 7. Pins 41 fixed in plunger 15 slide in grooves in the fuse body 7 to maintain the lead-outs 38 in position to register with the booster charges 39 when the parts are moved to the firing position.

When the fuse parts are in the unarmed position the lead-outs 38 are out of alignment with the booster charges 39, as seen in Fig. 5, and consequently accidental explosion of the detonator 37 would not ignite the booster charges 39 due to the fact that the lead-outs are sealed off from the booster charges by the close fit of plunger 15 with fuse body 7. However, when the projectile is fired the rotation thereof causes the detents 16 and 18 to be moved outwardly, leaving the plungers 10 and 15 free to move forwardly but such movement is prevented by spring 17 until impact of the projectile. Upon such impact the inertia of plunger 15 supplemented by that of the heavier auxiliary plunger 10 causes the plungers to move forward and strike primer 22 against firing pin 20, the explosion of primer 22 exerts sufficient force upon firing pin 23 to shear pin 24 and drive the firing pin 23 against primer 25 which in turn ignites delay pellet 34 and from the delay pellet the ignition is propagated to detonator 37 and thence by detonator lead-outs 38 to booster charges 39 which fire the bursting charge of the projectile.

Pins 42 extend through fuse cap 19 to secure the firing pin 20 in position and caps 43 close the outer ends of the spaces 28 into which cup 21 is expanded to lock the parts in firing position. Cap 19 is secured to fuse body 7 by drilling through the cap and into the fuse body after assembly, tapping the hole thus made in the fuse cap and securing a set screw 44 therein.

The invention herein described and claimed may be used and/or manufactured by or for the Government of the United States of America for governmental purposes without the payment of any royalties thereon or therefor.

I claim:

1. A projectile fuse, comprising a body having a cavity therein, booster charges in said body, a plunger and an auxiliary plunger slidable in said cavity, anti-friction means between said auxiliary plunger and said body, centrifugally releasable means to retain said plunger in an initial position; a detonator, detonator lead-outs adapted to be brought into registry with said booster charges by impact after the projectile is fired and a delay element in said plunger; said delay element including a first firing pin, shearable means to hold said firing pin in inactive position, a primer disposed to be strikable by said firing pin, a delay pellet adjacent said detonator, a baffle element between said primer and said pellet, and obturating ring between said delay element and said plunger, and a sensitive primer disposed to shear said shearable means and drive said firing pin against the first mentioned primer when said sensitive primer is detonated, there being passages leading outwardly from said sensitive primer; a deformable cup enclosing a portion of said plunger and overlying said passages; a cap on said body, a second firing pin in said cap to strike said sensitive primer, centrifugally displaceable means between said second firing pin and said delay element, there being recesses in said cap into which said deformable cup is expanded by the detona-

tion of said sensitive primer to lock said plunger in the forward position to which it is moved by impact whereby also said sensitive primer is caused to strike said second firing pin.

5 2. A projectile fuse, comprising a body having a cavity therein, booster charges in said body, a plunger and an auxiliary plunger slidable in said cavity, centrifugally releasable means to retain said plunger in an initial position; a detonator, detonator lead-outs adapted to be brought into registry with said booster charges by impact after the projectile is fired and a delay element in said plunger; said delay element including a first firing pin, shearable means to hold said firing pin in inactive position, a primer disposed to be strikable by said firing pin, a delay pellet adjacent said detonator, a baffle element between said primer and said pellet, and a sensitive primer disposed to shear said shearable means and drive said firing pin against the first mentioned primer when said sensitive primer is detonated, there being passages leading outwardly from said sensitive primer; a deformable cup enclosing a portion of said plunger and overlying said passages; a cap on said body, a second firing pin in said cap to strike said sensitive primer, centrifugally displaceable means between said second firing pin and said delay element, there being recesses in said cap into which said deformable cup is expanded by the detonation of said sensitive primer to lock said plunger in the forward position to which it is moved by impact whereby also said sensitive primer is caused to strike said second firing pin.

10 3. A projectile fuse, comprising a body having a cavity therein, booster charges in said body, a plunger and an auxiliary plunger slidable in said cavity, anti-friction means between said auxiliary plunger and said body, centrifugally releasable means to retain said plunger in an initial position; a detonator, detonator lead-outs adapted to be brought into registry with said booster charges by impact after the projectile is fired and a delay element in said plunger disposed to ignite said detonator; a primer carried in the forward end of said plunger, there being lateral openings through said plunger adjacent said primer, a deformable cup disposed around said end of the plunger and overlying said openings; a cap on said body, and a firing pin in said cap disposed to strike said primer when said plunger is moved forward by impact after the projectile is fired, there being recesses in said cap into which said cup is expanded by the detonation of said primer to lock said plunger with said lead-outs in registry with said boosters.

15 4. A projectile fuse, comprising a body having a cavity therein, booster charges in said body, a plunger and an auxiliary plunger slidable in said cavity, centrifugally releasable means to retain said plunger in an initial position; a detonator, detonator lead-outs adapted to be brought into registry with said booster charges by impact after the projectile is fired and a delay element in said plunger; said delay element including a first firing pin, shearable means to hold said firing pin in inactive position, a primer disposed to be strikable by said firing pin, a delay pellet adjacent said detonator, a baffle element between said primer and said pellet, an obturating ring between said delay element and said plunger, and a sensitive primer disposed to shear said shearable means and drive said firing pin against the first mentioned primer when said sensitive primer is detonated, there being passages leading outwardly from said sensitive primer; a deformable cup

enclosing a portion of said plunger and overlying said passages; a cap on said body, a second firing pin in said cap to strike said sensitive primer, centrifugally displaceable means between said second firing pin and said delay element, there being recesses in said cap into which said deformable cup is expended by the detonation of said sensitive primer to lock said plunger in the forward position to which it is moved by impact whereby also said sensitive primer is caused to strike said second firing pin.

5. A projectile fuse, comprising a body, a plunger slidable therein, means releasable by rotation after firing to retain said plunger in an initial position, a delay element in said plunger, means to propagate ignition from said delay element to the explosive charge of a projectile, a primer carried by said plunger to initiate functioning of said delay element, means to detonate said primer upon movement of said plunger to a predetermined position by impact after firing, an expansible member disposed around said primer to be expanded by explosion of said primer, and a member adjacent said expansible member, when said plunger is in said predetermined position, having cut away portions to permit expansion of said expansible member and engage said expansible member to hold said plunger in position to propagate ignition to said explosive charge of a projectile.

6. A projectile fuse, comprising a delay element including a container, a delay pellet therein, a baffle having one end seated against said pellet and a laterally extending flange at its other end and devious passages through said baffle, an obturating ring of plastic metal between said flange and an end of said container; a primer seated upon the flanged end of said baffle, a firing pin disposed to be movable against said primer, shearable means holding said firing pin normally away from said primer, a second primer disposed to drive said firing pin against the first mentioned primer when the second primer is detonated, and means disposed to be deformed by the products of detonation of said second primer and adapted to lock the aforesaid parts in the positions occupied by them at the time of detonation of said second primer.

7. A projectile fuse, comprising a delay element including a container, a delay pellet therein, a baffle having one end seated against said pellet and a laterally extending flange at its other end

and devious passages through said baffle, a primer seated upon the flanged end of said baffle, a firing pin disposed to be movable against said primer, shearable means holding said firing pin normally away from said primer, a second primer disposed to drive said firing pin against the first mentioned primer when the second primer is detonated, and means disposed to be deformed by the products of detonation of said second primer and adapted to lock the aforesaid parts in the positions occupied by them at the time of detonation of said second primer.

8. A projectile fuse, comprising a body means movable in said body including a delay device to propagate ignition to the explosive charge of a projectile, elements releasable during flight after firing to retain said means in an unarmed position until after firing, said means being movable to armed position by impact after release of said elements, a primer disposed to initiate, by its detonation, the functioning of said means, means to detonate said primer when said means is moved by impact as aforesaid, said movable means including means expansible by the products of detonation of said primer to lock said movable means in the armed position occupied thereby at the time of said detonation of said primer.

9. A projectile fuse, comprising explosion initiating means including a primer and a delay device, said means being movable from unarmed position to firing position by impact of the projectile, means to detonate said primer when so moved, and expansible means disposed around said primer to be expanded by the products of detonation of said primer to lock the aforesaid explosion initiating means in firing position for initiating the explosion through its said delay device.
